EMILE SAVOYE, OF PARIS, FRANCE.

CORSET.

SPECIFICATION forming part of Letters Patent No. 774,587, dated November 8, 1904.

Application filed January 25, 1904. Serial No. 190,503. (No model.)

To all whom it may concern:

Be it known that I, EMILE SAVOYE, manufacturer of corsets, a citizen of the Republic of France, residing at 35 Rue du Caire, Paris, in the Republic of France, have invented certain new and useful Improvements in Corsets, of which the following is a specification.

This invention relates to improvements in corsets, and more particularly to the whaleboning of corsets. Heretofore the whalebones have been arranged in an arbitrary manner simply for the purpose of stiffening the fabric, and that in a uniform manner from the top to the bottom of the corset. According to the present invention the whalebones are arranged in a rational and economic manner, in that they only extend in general on the intermediate part of the corset, which corresponds to the waist and which alone requires sufficient stiffness to properly maintain the upper part of the body. By the use of short whalebones limited to the waist part a great economy is realized in the manufacture, greater lightness is obtained, and the corset is rendered much more comfortable, because the upper and lower parts of the corset are kept pliable and the intermediate and whaleboned part cannot penetrate into the skin, while being at the same time sufficiently stiff to properly maintain the upper part of the body. The position and the direction of the whalebones are so arranged that each of the said whalebones is perpendicular or nearly perpendicular to the part of the waist-line it meets and applies itself flatly in a natural manner and from one end to the other on the body above and below the waist-line. Geometrically speaking, the line on which each whalebone extends is the line of contact of a cylindrical surface tangent to the surface of the body, the direction of the generating-lines of the said cylindrical surface being chosen nearly parallel to the corresponding portion of the waist-line, so that the said line of contact is a plane one. This arrangement has several advantages. In the first place it prevents the whalebones from becoming twisted and from bearing by their edge in certain places on the body. For the same reason the whalebones keep all their resistance and all

their stretching effect on the fabric. They are also much less liable to break, especially when what are called "spring-steel" whalebones are used. Furthermore, this arrangement allows the use of a wide whalebone in the place of a group of narrow whalebones located parallel one to another, as it was necessary to do heretofore when the position and the direction of the whalebones were arranged arbitrarily.

By way of examples the accompanying drawings show the arrangement of parts in which the present invention can be carried out and in which the assembling-lines of the parts of the corset are omitted as not being of any interest.

Figures 1 and 2 are perspective views showing, respectively, an elevation of the front and an elevation of the back of the corset.

In the form of carrying out the invention shown in the drawings all the whalebones 1 2 3 4 are short and none of them extend higher up than the waist or belt part of the corset. They rise up, preferably not so high up in front as behind, in a continuous manner. The front whalebones 1 are extended downward to the lower edge of the corset; but the other whalebones terminate at a point which is about intermediate between the narrowest part of the waist and the lower edge of the corset. In order to suitably maintain the upper part of the corset without rendering it stiff, ribbons 9 10 11, for instance, are used and arranged as shown in the drawings. On the side of the corset, above the row of whalebones, are stitched at 12 13 14 the crossed ends of two ribbons 9 10, which extend forward and slightly downward and of which the opposite ends extend beyond the front edge of the corset and can be tied in front to corresponding ribbons on the other side of the corset. The band 11 is arranged behind between the seam 12 and the back edge of the corset, and it is also fixed to the latter by the seams 12 15 16. By these means the upper part of the corset keeps its pliability and is at the same time prevented from getting out of shape, while the waist or belt part is suitably stiff.

The whalebones may be arranged in groups of two or more, as shown in Figs. 1 and 2.

It will of course be understood that without departing from the present invention the number of the whalebones may be varied according to the degree of stiffness it is desired 5 to obtain.

I claim—

1. In a corset, the combination of vertical whalebones the lower end of which lies at a certain distance above the lower edge of the 10 corset and the other end of which lies under the upper edge, and of ribbons arranged circumferentially on the upper part of the corset above the whalebones.
2. In a corset, the combination of whale-

bones the lower end of which lies at a certain 15 distance above the lower edge of the corset and of ribbons stitched onto the upper part of the corset above the whalebones, two of the said ribbons having their rear ends crossed and fixed on the side of the corset, and their 20 front ends being free to be tied together.

In testimony that I claim the foregoing as my invention I have signed my name in presence of two subscribing witnesses.

EMILE SAVOYE.
